SUCTION CLEANER

Elmer J. Kasper, Russell Township, Geauga County, Ohio,
assignor to Royal Appliance Manufacturing Company,
Cleveland, Ohio, a corporation of Ohio

Application December 15, 1958, Serial No. 53,763

Term of patent 7 years

(Cl. D9—2)

Fig. 2

Fig. 1

Figure 1 is a front elevational view of a suction cleaner showing my new design;

Fig. 2 is a side elevational view thereof;

Fig. 3 is a top plan view thereof; and

Fig. 4 is a bottom plan view thereof.

I claim:

The ornamental design for a suction cleaner, substantially as shown.
